UNITED STATES PATENT OFFICE.

ALEXANDER McGREGOR, OF BURLINGAME, CALIFORNIA.

VALVE.

Application filed May 16, 1924. Serial No. 713,827.

This invention relates to improvements in valves, and more particularly to that type of valve illustrated in United States Letters Patent No. 1,356,298 granted to me October 5 19th, 1920.

In addition to the advantages and uses for the valve set forth in the Letters Patent herein enumerated, the present invention presents an embodiment of valve wherein 10 a definitely defined seat is provided between the surface of the main valve and the point associated with the valve cage on which said main valve seats. A further object is to provide a construction wherein a greater 15 water passage area is provided in the cage than is afforded in the construction illustrated in my above mentioned patent.

Other objects are to provide a polygonal boss associated with the cage enabling the 20 easy engagement of the cage when it is desired to thread the valve structure into position, and to provide a defined seat between the main valve and the auxiliary valve. One 25 of the most important objects of this invention is to afford a double guide for the auxiliary valve in the form of outer and inner bearing surfaces, and to so construct the stem of the auxiliary valve that it receives the stem of the main valve and reciprocates 30 thereon, the periphery of the auxiliary valve affording a guide for the main valve when the two operate at the same time.

With the above mentioned and other objects in view, the invention consists in the 35 novel construction and combination of parts hereinafter described, illustrated in the accompanying drawings, and set forth in the claims hereto appended, it being understood, 40 that various changes in the form, proportion, size and minor details of construction within the scope of the claims may be resorted to without departing from the spirit or sacrificing any of the advantages of the invention.

To more fully comprehend the invention 45 reference is directed to the accompanying drawings, wherein

Figure 1 is a view in elevation of the preferred embodiment of my invention.

Figure 2 is a transverse vertical section 50 taken on line 2-2 of Figure 3, and

Figure 3 is a view in top plan.

In the drawings the numeral 1 indicates a coupling member having a threaded periphery 2 and a shouldered flange 3, the surface 55 of which is threaded and the upper face of which provides a seat 4 for the main valve.

Threaded to the periphery of the flange 3 is a cage 5, the outer wall of which is ported or cut away as at 6 for approximately its vertical area, and said wall terminates in 60 a converging or dome portion 7 formed with a stem guide 8, from the lower end of which depends a boss 9. The periphery of the wall forming the dome 7 is of polygonal configuration as at 10 to receive a wrench or other 65 valve mounting tool. Like in my patent above mentioned, I mount within the cage to control the opening 11 a main plate or disk valve 12, having a relatively wide peripheral edge 13 which is guided by frictional contact with the inner face of the parallel portion of the wall 5. The under surface of the main valve is cut away or recessed as at 14 to afford a definite seat 15 for contacting with the face 4. Also like 70 the valve in my previously mentioned patent, the main valve in the present case is ported as at 16, and the passage of fluid through the ports is controlled by an auxiliary plate or disk valve 17 seating on one 75 face of the main valve 12. A relatively heavy spring 18 is coiled about the boss 9, and bearing on the upper surface of the main valve 12 normally maintains the same seated, and a comparatively light weight 80 spring 19 bearing on the auxiliary valve 17 maintains the auxiliary valve seated on the main valve 12. Centrally from the auxiliary valve 17 extends a tubular guide 20, the 85 end of which projects into the guide opening 90 8 and the peripheral surface thereof has fitting contact with the wall of the guide opening 8. Into the tubular portion 21 of the member 20 extends the valve 22 of the main valve 12, it snugly fitting therein. 95 Thus it will be observed that the main and auxiliary valves are both doubly guided, the wear thereon is reduced, and the liability of the same to wear unevenly in their movement is reduced to a minimum.

Having thus described my invention, what I claim as new and desire to protect by Letters Patent of the United States is:—

1. A valve unit, comprising a coupling member having a threaded flange formed with a valve seat, a cage having a cylindrical portion threaded at one end on said flange and providing a cylindrical guide wall on the interior thereof beyond said member, the free end of the cage having a sleeve of reduced size arranged concentrically with respect to the cylindrical portion, a main valve 105 110

mounted in the cage for engagement with said seat, and having the periphery in bearing contact with the cylindrical guide wall for sliding movement therein, said main valve having an axially projecting stem, and a secondary valve controlling passages formed in the main valve having a tubular stem having the interior provided with a 10 slideable bearing fit on the stem of the main valve, and the exterior provided with a slideable bearing fit in the sleeve of said cage, whereby each valve is provided with a spaced two bearing support and guideway in said cage through the cooperative assembly of 15 each valve with the other.

2. A doubly guided double valve comprising in combination with a metallic seat, of

a metallic faced disc valve having a stem and a port, a second metallic faced disc valve arranged to overlie said port and having a 20 tubular stem slidably receiving the stem of the first valve, independent spring means normally operating each valve to seated position, and a cage having peripheral guiding means for the periphery of the first valve, and a central guiding means for the tubular stem of the second valve, said peripheral and central guiding means and the cooperation of both valves providing a double guide for the independent operation of each valve. 25 30

In testimony whereof I have signed my name to this specification.

ALEXANDER McGREGOR.
